(57) **CLAIM**

The ornamental design for a chair, as shown and described.

DESCRIPTION

FIG. 1 is a front perspective view of a chair, showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The dotted broken lines represent stitching that forms part of the claimed design.

The dashed broken lines depict portions of the article that form no part of the claimed design.

1 Claim, 6 Drawing Sheets
